UNITED STATES PATENT OFFICE.

HOWARD D. CHAPMAN, OF BALTIMORE, MARYLAND.

RATCHET SCREW DRIVER.

Application filed December 21, 1921. Serial No. 523,975.

To all whom it may concern:

Be it known that I, HOWARD D. CHAPMAN, citizen of the United States, residing at Baltimore, State of Maryland, have invented 5 certain new and useful Improvements in Ratchet Screw Drivers, of which the following is a specification.

This invention relates to certain new and useful improvements in ratchet screw drivers 10 and has particular reference to an improved form of ratchet screw driver equipped with an enlarged power applying member whereby the blade may be rotated in clockwise and counter-clockwise directions without a great 15 deal of manual effort.

Heretofore in using screw drivers it has been necessary to apply a longitudinal pressure from the handle end of the driver, at the same time apply a rotary movement to 20 the handle of the screw driver. In applying the longitudinal pressure and giving a rotary movement to the handle it has been found in lots of instances extremely difficult, and, to overcome this difficulty I have provided an improved ratchet screw driver. 25

One of the principal objects of my invention is to provide a ratchet screw driver capable of being turned in clock or counter-clockwise direction by providing the screw 30 driver with an intermediate rotating handle member. By virtue of this rotating member, the shank of the driver may be placed in the nick of a screw and longitudinal pressure kept on the shank by applying pressure 35 at the outer handle member, and to turn the shank it is only necessary to rotate the intermediate member, which imparts rotation to the shank by virtue of a ratchet mechanism. It will be seen that the principle of 40 a three-part handle is to have a lower stationary part and an upper stationary part secured to the shank, a central rotating part, a ratchet connection between the lower stationary part and the central rotating part; 45 thus it follows, it is only necessary when using the driver to rotate the same, apply a rotary motion to the intermediate member, which motion is transmitted to the shank through the lower stationary member, the 50 upper stationary member being used as a shank holding handle.

The primary object of the present invention is, therefore, to provide an improved means whereby the blade of the screw driver 55 may be readily and more effectively rotated in clockwise or counter-clockwise directions,

said means being so constructed as to render it necessary to only slightly modify the present type of screw driver.

It is desirable that the screw driver be 60 equipped with the usual blade, having one end constructed to nicely fit the nick in the head of a screw, a pair of spaced stationary handle members secured to the blade, and an enlarged blade operating member located 65 between the two stationary members. The three, namely, the two stationary members and operating member, constituting the handle of the driver.

I preferably accomplish the above object 70 by making the handle in three parts, securing two of the parts rigidly to the shank or blade of the driver and the intermediate section being free to rotate about the shank or blade and being connected to the blade by a 75 ratchet member, which consequently transmits the rotary movement of the intermediate member to the blade.

A further object of the invention is, the provision of a means whereby the ratchet 80 member may be reversed so that the turning movement of the blade in either direction may be accomplished.

With the above general objects in view and others that will become apparent as 85 the nature of the invention is better understood, the same consists in the novel form, combination and arrangement of parts hereinafter more fully described, shown in the accompanying drawing and claimed. 90

In the drawing wherein like characters of reference indicate corresponding parts throughout the several views,

Figure 1 is a side elevation of the screw 95 driver partly in section and showing the same complete and as made in accordance with my invention,

Figure 2 is a transverse sectional view taken on the line 2—2 of Figure 1, and looking in the direction indicated by the arrows, 100

Figure 3 is a transverse sectional view taken on the line 3—3 of Figure 1, looking in the direction of the arrows,

Figure 4 is a transverse sectional view taken on the line 4—4 of Figure 1, and 105 looking in the direction indicated by the arrows, and,

Figure 5 is a detail perspective view of the ratchet operating member.

Referring to the drawing in detail, 5 indicates an annular shank or blade commonly used in screw drivers, and this blade

is provided at one end with inclined faces to provide a screw nick engaging point 6, this also being the usual construction of screw driver blades or shanks. The opposite end of the shank 5, has secured thereto the handle which serves to rotate the blade in clockwise or counter-clockwise directions, the construction of which handle will be hereinafter more fully described.

10 The handle above referred to consists in its construction three parts, the lower ferrule member 7, an enlarged power applying member 8, and the upper holding member 9. The lower ferrule member 7 and 15 the upper holding member 9 are rigidly secured to the shank or blade 5 by a suitable fastening means 10, such as a pin or rivet extending transversally through the members 7 and 9 and the shank 5. The intermediate power applying member 8 is 20 freely rotatable about the shank 5 and between the opposing faces of the members 7 and 9, respectively, the purpose for which will be hereinafter more fully described.

25 This member 8 has provided in one of its ends an annular recess 11, which is adapted to receive or have fitted therein, a ratchet member 12. The ratchet member 12 is secured in this recess 11, by suitable 30 fastening means 13, such as nails, screws, or the like, the heads of which are countersunk so as to avoid contact between the heads of the fastening means 13 and the opposing face of the ferrule member 7 when 35 the power applying member 8 is rotated thereon.

To cooperate with the power applying member 8, I form in the ferrule member 7, a recess 14 which communicates with the recess 11 of the intermediate member 8, and 40 also extends through the ferrule member 7 to the outer side thereof. Positioned within the recess 14 of the ferrule member 7, is a ratchet engaging dog 15, which is provided at one end with an inclined ratchet wheel engaging face 16, while its opposite end terminates into a reduced circular shank 17. The reduced circular shank 17, of the dog 15, is surrounded by a suitable 45 coil spring 18, which is also located in the recess 14 of the ferrule member 7. The reduced shank 17, has its terminal extending out through and beyond a transverse recess 19, formed in the member 7. A handle or 50 operating member 20, is secured to the terminal of the shank 17 and lies between the walls of the recess 19 of the member 7, and when in this position the working face 16 of the dog 15 is engaged between the walls 55 of one of the teeth of the ratchet wheel 12, thus permitting the driver blade 5 to be rotated in one direction by virtue of the fact that motion is transmitted from the power applying member 8, through the 60 ratchet wheel 12, dog 15, ferrule member 65

7, to the blade 5. It is, of course, understood that by virtue of the inclined working face 16 of the dog 15, that counter-clockwise rotation of the intermediate member 8 may be had, due to the fact that the inclined face 16 will freely ratchet over the walls of the teeth in the ratchet wheel 12.

70 The screw driver as shown in Figures 1 and 2, can be turned in a clockwise direction and the member 8 rotated or ratcheted in a counter-clockwise direction, and to reverse this movement of the blade 5 and the member 8, it is only necessary to grasp the handle member 20, apply a downward pressure thereon, which withdraws the dog 15 against the spring 18, and out of engagement with the ratchet wheel 12, permitting the handle member 20 to be turned in the transverse slot 19, consequently causing a reversing of the working 80 face 16, which permits of the reverse motion of the blade 5 and member 8 in the manner previously described.

85 It is understood that the blade 5 can be substituted for a socket and tools of various kinds placed therein. It is also being understood, however, that only tools desiring a revolving movement could be used.

In practice, it is only necessary when using this screw driver to apply the point 6 of 90 the blade 5 in the nick of a screw head, grasp the power applying member 8 in the right hand, holding the member 9 in the left hand, and by applying a rotary motion to the power applying member 8, which in turn 95 will transmit motion to the blade 5 through the ratchet mechanism. It is only necessary to ratchet the member 8 in a reverse direction to continue turning the blade 5 in a 100 clockwise direction.

105 It will be clearly understood that a screw driver made in accordance with this invention allows for greater leverage and increased driving force, due to the fact that a direct rotary motion is applied to the enlarged power applying member 8, relieving the dual function of holding the driver by longitudinal force and at the same time rotating the driver.

110 It is believed that the construction and 115 operation of the present invention as well as the advantages thereof will be readily understood by those skilled in the art, and while the form of the invention herein shown and described is what is believed to be the preferable embodiment thereof, it is nevertheless to be understood that minor changes 120 may be made without departing from the spirit and scope of the invention as claimed.

125 What is claimed is:

1. A ratchet screw driver of the class described, comprising a blade having a sectional handle secured to one end thereof, said handle including three (3) parts, spaced upper and lower sections rigidly secured to 130

- the blade, an intermediate power applying section freely rotatable on the blade, said intermediate section having a recess formed in its lower end, a ratchet wheel secured in 5 said recess, said lower rigid section provided with a recess communicating with the first named recess, an operating dog mounted in the recess of the lower section, a spring surrounding said dog to normally urge it into 10 engagement with the ratchet wheel of the power applying section, whereby upon applying rotary motion to said section it will be converted to the blade, and a ratchet dog operating means secured to the lower end of 15 the ratchet dog and located exteriorly of the lower section, whereby the rotary motion of the blade may be governed.
2. A screw driver of the class described including a shank having a sectional handle at one end, said handle including spaced upper and lower sections rigidly secured to 20 said shank, an intermediate power applying section of a length greater than the upper and lower sections and freely rotatable on the shank, and a ratchet mechanism carried 25 by the lower rigid section and adapted for engagement with the opposing face of the intermediate section whereby said shank may be rotated by operating the power applying intermediate section. 30

In testimony whereof he hereunto affixes his signature.

HOWARD D. CHAPMAN.
